UNITED STATES PATENT OFFICE.

HENRY G. LEACH AND JOSEPH S. LEACH, OF BROOKLYN, NEW YORK.

AMPLIFYING RECEIVER.

Application filed April 26, 1922. Serial No. 556,645.

To all whom it may concern:

Be it known that we, HENRY G. LEACH and JOSEPH S. LEACH, citizens of the United States and Great Britain, respectively, and residents of Brooklyn, in the county of Kings and State of New York, have invented certain new and useful Improvements in Amplifying Receivers, of which the following is a specification.

10 The invention relates to so-called "loud speaking" apparatus or electrical amplifying receivers, as employed in connection with the reception of radio signals and the like, or for the transmission of phonographically reproduced sounds. It has for its object, in a device of this type, to provide for the adjustment of the receiving mechanism in accordance with variations in the operating current such, for example, as may be produced by tube voltage changes. A further object of the invention consists in means for setting the adjusting device and for regulating the tension on the operating arm of the adjusting means.

15 20 25 The nature of the invention, however, will best be understood when described in connection with the accompanying drawings, in which—

Fig. 1 is a front elevation and Fig. 2 is a side elevation of a loud-speaker embodying the invention.

Fig. 3 is a detail vertical section of the base portion thereof.

Fig. 4 is an underneath view of the loud-speaker.

Fig. 5 is a fragmentary detail view.

Similar characters of reference designate corresponding parts thruout the several views.

40 Referring to the drawings, 10 designates a horn or other suitable resonator of well-known or special design and which it is preferred to employ with the receiver, the horn then being secured in a base 11 made hollow to encase the receiver mechanism, as shown. Base 10 is provided at its lower portion with a slit 12 or elongated opening into the interior of the base and thru which is inserted for limited oscillation therein an operating handle 13 for the tension adjuster of the receiver diaphragm.

At the upper portion of the base and in proximity to its end is mounted the receiver diaphragm 15 of any well-known or special type; and against the same is tensioned, thru the attraction of an armature 16 by

magnet 17 of the receiver, a pivoted lever 18, the latter being unattached to the diaphragm. No claim, however, is made to this construction specifically, as the invention consists in the means, in connection with a tensioned and lever actuated diaphragm, for regulating the degree of tension between diaphragm and lever.

For example, the entire receiver mechanism is encased and carried by a container 20 mounted for limited reciprocation in the upper portion of the base 11, suitable leads 21 from external binding posts 22 being connected with the receiver mechanism in the container 20. Container 20 is supported in the base 11 by means of an axial stud 23 projecting downwardly therefrom, the same being surrounded by a sleeve 24 externally threaded and held to the stud by a cap 25 and between the latter and the bottom of the container 20. Sleeve 24 works in a threaded opening of a cross-bar 26 and in a similar opening of a bridge 27, the bar 26 being secured to the base 11 and the bridge 27 to the bar 26. Between the cross-bar and bridge and embracing the sleeve 24 is a forked member 28 with threaded jaws to fit the sleeve to which it may be locked by means of a screw 29 passing thru the outer ends of the jaw members. The inner end of arm 13, moreover, is secured to the forked member 28 so that movement of the former will be reproduced in the latter to oscillate the sleeve 24. Oscillation of the latter thus effects a reciprocation of the container 20 to vary the tension between the lever 18 and its associated diaphragm 15 in accordance with the current, or rather voltage, conditions; and renders thereby a more satisfactory reproduction of the sound.

It will be appreciated, however, that this adjustment is limited to the extent of oscillation of the arm 13. Should it be desired to reset same to change the initial tension, this may conveniently be accomplished by merely loosening the screw 29 to remove the tension of the jaws of fork 28 upon the sleeve 24 and thus permit of freely moving the former with reference to the latter, whereupon the jaws may again be tightened and a new, but similar, degree of adjustment is available. Moreover, it may occur that the movement of the arm 13 is too loose or too tight to suit the taste of the particular operator; and provision is made to vary the tension thereon as by an adjusting screw

30 which passes thru the bridge 27 and works into the cross-bar 26, so that in drawing the two slightly together or separating same by means of said screw, the resistance placed upon the rotation of the sleeve 24 is correspondingly altered.

We claim:—

1. An electrical amplifying receiver, comprising a hollow base member with opening 10 therein, a diaphragm mounted in the base, a container reciprocable in said base, electro-magnetic means mounted therein to actuate said diaphragm and including a tensioned lever contacting therewith, a stud 15 extending from said container, an externally threaded sleeve mounted about said stud, a cap holding same thereto and between itself and the container, a forked member embracing the sleeve to rotate same, and threaded 20 means engaging the sleeve and secured to the base.

2. An electrical amplifying receiver, comprising a hollow base member with opening therein, a diaphragm mounted in the base, 25 a container reciprocable in said base, electro-magnetic means mounted therein to actuate said diaphragm and including a tensioned lever contacting therewith, a stud extending from said container, an externally 30 threaded sleeve mounted about said stud, a cap holding same thereto and between itself and the container, a forked member embracing the sleeve to rotate same, threaded means 35 engaging the sleeve and secured to the base, and an arm secured to the forked member and extending thru the opening of the base and beyond same.

3. An electrical amplifying receiver, com-

prising a hollow base member with opening 40 therein, a diaphragm mounted in the base, a container reciprocable in said base, electro-magnetic means mounted therein to actuate said diaphragm and including a tensioned lever contacting therewith, a stud 45 extending from said container, an externally threaded sleeve mounted about said stud, a cap holding same thereto and between itself and the container, a forked member embracing the sleeve to rotate same, a cross-bar secured to the base and having a threaded 50 opening into which fits the said sleeve, a bridge secured to the cross-bar and having a threaded opening into which fits the said sleeve, and means to draw the said cross-bar and bridge slightly together. 55

4. An electrical amplifying receiver, comprising a hollow base member with opening therein, a diaphragm mounted in the base, a container reciprocable in said base, electro-magnetic means mounted therein to 60 actuate said diaphragm and including a tensioned lever contacting therewith, a stud extending from said container, an externally threaded sleeve mounted about said stud, a cap holding same thereto and between itself 65 and the container, a forked member embracing the sleeve to rotate same, means to lock and release the forked member to said sleeve, and threaded means engaging the sleeve and secured to the base. 70

Signed at New York, in the county of Kings and State of New York, this 22nd day of April, A. D. 1922.

HENRY G. LEACH.
JOSEPH S. LEACH.
